Henry J. Talge and Cecil Martyr, Kansas City,
Mo., assignors to John C. Hockery, Foster L.
Talge, and Henry J. Talge, doing business as Rival Manufacturing Company, Kansas City, Mo.

Application May 28, 1945, Serial No. 119,781

Term of patent 14 years

(Cl. D22—2)

To all whom it may concern:

Be it known that we, Henry J. Talge and Cecil Martyr, citizens of the United States, residing at Kansas City, in the county of Jackson and State of Missouri, have invented a new, original, and ornamental Design for a Can Opener, of which the following is a specification, reference being had to the accompanying drawing, forming part thereof, in which

Fig. 1 is a perspective view of a can opener showing our new design, and

Fig. 2 is a perspective view of the reverse side thereof.

We claim:

The ornamental design for a can opener, substantially as shown.

HENRY J. TALGE.
CECIL L. MARTYR.
